(57) **CLAIM**

The ornamental design for a proppant vessel, as shown and described.

DESCRIPTION

FIG. 1 is an upper perspective view of the proppant vessel showing our design.

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The features presented in broken lines are for environmental purposes only and form no part of the claimed design.
